INVENTOR

Thomas A. Cole,
BY
Akbar S. Paramore.
ATTORNEY.

UNITED STATES PATENT OFFICE.

THOMAS A. COLE, OF INDIANAPOLIS, INDIANA, ASSIGNOR TO ELSO KELLER AND CALVIN L. HOLLOWELL, OF SAME PLACE.

COMBINED CIGAR CLIPPER AND REGISTER.

SPECIFICATION forming part of Letters Patent No. 592,106, dated October 19, 1897.

Application filed February 8, 1897. Serial No. 622,524. (No model.)

To all whom it may concern:

Be it known that I, THOMAS A. COLE, a citizen of the United States, residing at Indianapolis, in the county of Marion and State of Indiana, have invented certain new and useful Improvements in a Combined Cigar Clipper and Register; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 My invention relates to improvements in combined cigar clippers and registers of that class adapted to clip the tips from cigars preparatory to lighting them, and at the same time registering the number of cigars so 20 clipped.

The objects of my invention are, first, to provide a combined cigar clipper and register that will be neat in appearance and reasonably cheap of manufacture; second, that 25 will by introducing the cigar-tip in one of the apertures in the top of the case release the cutting blade or knife so the operating-lever may be depressed, thereby sliding the knife forward and clipping the tip; third, that will 30 register each cigar clipped, and automatically sound an alarm whenever a certain predetermined number of cigars has been clipped; fourth, that will prevent the operation of the registering device or the depression of the 35 operating-lever until the knife is released by the introduction of the cigar-tip; fifth, to provide a means for instantly resetting the knife and raising the operating-lever when it is released; sixth, to provide a receptacle into 40 which the cigar-tips may fall, and, seventh, to provide a cigar clipper and register that may be used by merchants as a means for attracting patronage. These objects I attain by means of the construction and combination 45 of parts shown in the accompanying drawings and set forth in the following specification.

In the drawings, Figure 1 is a perspective view. Fig. 2 is a vertical sectional view; and 50 Fig. 3 is a top plan view with a portion of the top removed to show the registering devices,

the knife, knife-guides, and locking-spring being indicated by dotted lines.

A is the case, provided with a base B, said case having in the rear end a drawer C, and in the front end the slot D, within which the lever E operates. In the top is a removable plate F, secured by screws a, and provided with the round openings b. The top also has the openings c and c', through which the 60 numbers upon the register appear.

The registering mechanism, supported by the journals d, d', and d'', is placed in the front end of the case A and is suitably mounted in the frames G. Upon the journal d is mounted the lever E, the ratchet-wheel e, and the operating-wheel f. Upon the journal d' is mounted the register-wheel H, upon the periphery of which are the numerals running from "0" to "100," the friction-wheel g, and the operating-wheel f'. Upon the journal d'' is mounted the register-wheel H' and the friction-wheel g'. The register-wheel H' has upon its periphery numerals running from "100" to "1000."

75 The clipping mechanism is secured to the under side of the top of the case A, and consists of the knife h, which slides in the guides i, the knife-retaining spring-plate k, and the connecting-lever l.

80 The lever E, which is mounted upon the journal d, is provided at its outer end with a button m, by which it is depressed, and its inner end is formed at right angles to the main portion, the upper end thereof being pivotedly connected with the lever l. A 85 spring-dog n, which engages the ratchet-wheel e, is secured to the lever E, and a coil-spring o, secured at one end at the top A and at the other end to the lever E, is adapted to hold said lever normally in the raised position shown in Fig. 2. A bell r is fastened to the frame G, and a striker s, pivotally secured to said frame, is adapted to strike said bell. The operating-wheel f, 90 upon the shaft d, is provided with the projecting pin t and a friction-lug v. The small coil-spring u is provided for the purpose of causing the striker to deliver a sharp blow upon the bell when the opposite end thereof 95 is released by the pin t on the operating-wheel f. The drawer C, which receives the

cigar-tips, is provided with a suitable lock *p* and a knob *w*. The journals *d*, *d'*, and *d''* are each provided with the tension-springs *x*, their purpose being to tension said journals 5 against too free movement, should the lever *E* be operated with some violence, thereby preventing the register-wheels from turning too far by their own momentum. Upon the operating-wheel *f'* is a friction-lug *v'*, which 10 is adapted to engage the friction-wheel *g'*. The spring-plate *k*, which is secured at one end to the rear wall of the case *A*, extends forward far enough to cover the circular openings *b*, and has a small upwardly-projecting 15 lug *y* in its center near the front end, which is adapted to catch and hold the knife against forward movement. Downwardly-projecting ears *z*, secured to the knife *h*, are provided, to which the rear end of the connecting-lever 20 *l* is pivotally attached.

In operation, the cigar-tip is inserted in one of the circular openings *b* in the plate *F*, thereby depressing the spring-plate *k*, causing the lug *y* to release the knife *h*. The lever *E* is then pressed downwardly, which 25 causes the knife to slide forward within the guides *i*, by reason of its being connected therewith by the lever *l*, and thereby clips the tip of the cigar. As soon as the lever is 30 released the spring *O* raises it, which causes the spring-dog *n* to drop back one notch on the ratchet-wheel *e*, and at the same time causes the knife *h* to slide back, allowing the 35 spring-plate *k* to resume its place with the lug *y*, holding the knife against forward movement. The depression of the lever *E* causes the spring-dog *n* to slightly rotate the ratchet-wheel *e*, it being understood that said ratchet-wheel, as well as the operating-wheels, friction-wheels, and registering-wheels, are all 40 fixedly mounted upon the journals *d*, *d'*, and *d''*.

The registering mechanism illustrated in the drawings shows the device arranged to register by tens. Therefore by starting at "0" 45 the lever *E* will be depressed ten times when the journal *d* will have made one complete revolution, and the friction-lug *v* on the operating-wheel *f* will have engaged the friction-wheel *g* and caused it to move the register-wheel *H* to "10," indicating that ten cigars have been clipped. At the same time the projecting pin *t* on the operating-wheel *f* will have depressed the free end of the 50 striker *s*, thereby extending the spring *u*, and as the pin *t* releases the striker the spring will cause it to strike the bell *r* with some force, sounding an alarm and drawing attention to the fact that ten cigars have been 55 clipped. This will be repeated at every complete revolution of the journal *d*. When one hundred cigars have been clipped, the friction-lug *v'* on the operating-wheel *f'* will engage the friction-wheel *g'* and move the register-wheel *H'* to "100." This will continue 60 until one thousand is registered, when the machine will begin counting again at "0."

The combined clipper and register may be

used by merchants to attract patronage by offering a cigar free to the purchaser who in clipping his cigar causes the bell to ring, or 70 for every tenth cigar clipped.

It will be understood that the particular plan of numbering shown in the drawings may be changed without in any way affecting the principles of my invention. 75

The purpose of the removable plate *F* is to provide an easy means for obtaining access to the knife for the purpose of cleaning or sharpening it, or for oiling the guides.

Having described my invention, what I 80 claim, and desire to secure by Letters Patent of the United States, is—

1. A combined cigar clipper and register having a sliding cutter or knife normally held against forward movement by means of a 85 spring-plate; a spring-plate adapted to be depressed by the tip of a cigar; an operating-lever for sliding the knife forward to clip the cigar-tips when said lever is depressed, and at the same time actuate the registering mechanism; a registering mechanism consisting of a ratchet-wheel, operating-wheels provided with friction-lugs, friction-wheels and registering-wheels having numerals upon their peripheries, and one of said operating-wheels 90 in turn sounding an alarm when a certain predetermined number of cigars have been 95 clipped, substantially as set forth.

2. A combined cigar clipper and register consisting of a case *A*, having a slot *D*, in 100 one end, and a drawer *C*, in the other, and having register-openings *c*, and *c'*, and a removable plate *F*, in the top thereof, said plate having two circular openings *b*; a cigar-clipping mechanism consisting of the knife 105 *h*, the guides *i*, the spring-plate *k*, and lever *l*; a registering mechanism mounted in frames *G*, consisting of journals *d*, *d'*, and *d''*, a ratchet-wheel *e*, operating-wheels *f*, and *f'*, having friction-lugs *v*, and *v'*, friction-wheels 110 *g*, and *g'*, registering-wheels *H*, and *H'*; an alarm device consisting of a bell *r*, and a striker *s*, actuated by a pin *t*, upon the operating-wheel *f*, and spring *u*; and an operating mechanism consisting of a lever *E*, mounted 115 upon the journal *d*, having a spring-dog *n*, secured thereto, said lever held normally in a raised position by means of the coil-spring *o*, all substantially as shown and described.

3. In a combined cigar clipper and register, 120 the combination of the case *A*, having a removable plate *F*, provided with circular openings *b*, the register-openings *c*, and *c'*, the drawer *C*, and the slot *D*, with the cigar-clipping mechanism adapted to be released by 125 placing the cigar-tip within one of the openings *b*, in the case, and to be operated by the lever *E*, the operating-lever *E*, and the registering mechanism operated by a spring-dog secured to the lever *E*, all substantially as 130 shown and described.

4. In a combined cigar clipper and register, the combination of the operating and clipping mechanism consisting of the lever *E*,

the coil-spring *o*, the spring-dog *n*, the lever *l*, the knife *h*, having the ears *z*, the guides *i*, and the spring-plate *k*, having the lug *y*, with the registering and alarm devices consisting of the ratchet-wheel *e*, and the operating-wheel *f*, having the friction-lug *v*, both mounted on the journal *d*; the friction-wheel *g*, the operating-wheel *f'*, having the friction-lug *v'*, and the register-wheel *H*, all mounted on the journal *d'*; the friction-wheel *g'*, and the register-wheel *H'*, both mounted

on the journal *d''*; the bell *r*, and the striker *s*, actuated by the spring *u*, and the pin *t*, upon the operating-wheel *f*, substantially as set forth.

In testimony whereof I affix my signature in presence of two witnesses.

THOMAS A. COLE.
